10 Sheets-Sheet 9

UNITED STATES PATENT OFFICE.

RODNEY G. RICHARDSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed June 25, 1923, Serial No. 647,453. Renewed June 16, 1927.

The present invention relates in general to automatic telephone systems, but more particularly to such systems as employ the so-called "director" for controlling the establishment of connections, and the general object is to provide an improved type of director which is adapted to translate from one system of notation to another. More specifically, the object is to provide a director, or translator and sender, for use in a multi-office automatic telephone system in which the numbers are received according to one system of notation by "directors" of the same general type as is disclosed in the co-pending application of Nelson, Serial No. 573,175, filed July 6, 1922, and are translated into a system of notation employing fewer separate characters before being transmitted to the automatic switches.

This invention is a subsequent development of that shown in the above referred to Nelson application as well as of the following prior applications. Richardson et al., S. N. 547,866, filed Feb. 23, 1922; Richardson et al., S. N. 638,551, filed March 29, 1922; Ray, S. N. 589,985, filed Sept. 23, 1922; Gillings, S. N. 598,239, filed Nov. 1, 1922.

There are various other objects having to do mainly with the detailed workings of the system that can be gathered best from the detailed description of the operation of the system.

In illustrating the invention, it will be assumed that the numbers received by the directors are written according to the system of notation in which twenty characters are used, and are then translated into numbers written according to the decimal system of notation. The twenty character system of notation permits each of a large number of subscribers to be listed by means of a number containing a small number of characters as compared with the number of characters required when the decimal system of notation is used to list a like number of subscribers. The advantages of using a system of notation in which a reduction of the number of characters in the number is permitted have been set forth in numerous patents, and the greatest one is probably the advantage gained on account of the fact that the numbers, being shorter, are much more easily carried in mind. As stated above,

the numbers are translated into the decimal system before being sent out to the automatic switches. This enables the standard ten step automatic switches to be used and permits the trunking local to each office to be laid out according to the trunking system which has become standard for single office systems and for the individual offices in a multi-office system laid out for use in connection with a decimal numbering system.

It has been chosen to describe the invention in connection with a system having an ultimate capacity of 160,000 lines. Since the twenty character system of notation is used, and since 20^4 is 160,000, each of the numbers for this system contains only four characters, whereas six characters are required for each of the numbers in a system of the above size when the decimal system of notation is used.

Since the system of notation used employs 20 characters, and since there are 160,000 lines in the system, the system can be very conveniently divided into twenty offices of 8,000 lines each. In this case, the choice of offices is made upon the first operation of the calling device. However, when the standard ten-step switches are employed for trunking, they cannot be utilized to their full capacity when an office contains only 8,000 lines; that is, when only 8,000 lines are in an office, two levels of the thousands selectors in that office are dead. For that reason, and for the further reason that it is a practice long established to place approximately 10,000 lines in one office, it has been decided to divide the system into offices of 10,000 lines each, making sixteen offices in all.

In the accompanying drawings comprising Figs. 1-11, inclusive, a sufficient amount of equipment is shown in a system employing the principles of the invention to enable the invention to be understood. Figs. 1-3, inclusive, show the relation between the numbers received by the director and the numbers set out to the automatic switches. Figs. 4-10, inclusive, are circuit diagrams and Fig. 11 is a layout showing how Figs. 4-10, inclusive, should be placed together in order to be understood.

Referring now particularly to Fig. 1, six-

teen rectangles, each representing an office of the system, are shown therein. These rectangles, as may be seen, are labeled office No. 1, office No. 2, etc., the numbers 1 to 4, 5 to 9, 11 to 14, and 16 to 19, inclusive, being used. Two formulas, if they may be so termed, are written inside each rectangle and they represent the numbers that are assigned to each office. For example, the 10 upper formula of office No. 1, represents 8,000 numbers and is 1—(1-20)—(1-20)—(1-20), which means that all numbers beginning with 1 are assigned to this office, the expression (1-20) meaning that the corresponding character may be anything from 1 to 20.

It may be here explained that in all probability ten of the characters used for listing numbers according to the twenty character 20 system of notation will be the digits 1, 2, etc. to 9, and 0; and that the remaining ten characters will comprise ten letters of the alphabet. Notwithstanding this, however, the above formulas, as well as the following 25 ones, are for the sake of clarity, written just as though the twenty characters are the numbers 1, 2, etc. to 20, with a dash (—) separating each character from the others.

To resume the explanation of Fig. 1, the 30 block of numbers beginning with 5 are divided into four equal parts of 2,000 numbers each, and one part is assigned to each of the first four offices, as is indicated by the lower formulas of these offices. It is 35 apparent from these formulas that, if the first character of a number is 5 and the second character is anything from 1 to 5, inclusive, the number belongs to the first office, while if the first character is 5 and the 40 second character is other than 1 to 5, inclusive, the number belongs to one of the other offices, either the second, third, or fourth. A casual examination will reveal that the same general numbering scheme is 45 carried out for the remaining offices.

Referring now particularly to Fig. 2, which is a more detailed layout of numbers assigned to office No. 1, Fig. 1, the numbers are laid out in 100 groups of 100 each, according to the capacity of a standard connector switch. These groups are numbered from 11, in the lower left hand corner, to 00, in the upper right hand corner, in accordance with the standard layout of a 10,000 line office, using ten-step thousands selectors 55 and ten-step hundreds selectors.

Since the system of notation used contains twenty characters, and since twenty taken twice as a factor equals 400, the numbers 60 may be conveniently split up into blocks of 400 numbers each. That being the case, the 10,000 numbers of this office are divided into twenty-five blocks of 400 numbers each and the first block of numbers in this 65 office may be represented by the formula

1—1—(1-20)—(1-20), which means that the first and second characters of all the numbers in this block are 1 and 1, respectively, while the third, as well as the fourth characters, run from 1 to 20. Since the capacity 70 of a standard connector switch is only 100 numbers, this 400 number block must be split into four parts of 100 numbers each. The first part is represented by the formula 1—1—(1-5)—(1-20), the second by the formula 1—1—(6-10)—(1-20), etc., as may be seen by referring to the first four connector groups 11-14, inclusive, which are the ones to which the numbers in question are assigned. The second 400 block of numbers 80 is assigned to the four connector groups 15-18, inclusive, the third block to the first four connector groups in the second thousand, which are the groups 21-24, inclusive, the fourth block to the next four groups 25-28, 85 inclusive, while the fifth 400 number block is assigned to the ninth and tenth connector groups in the first and second levels which are the connector groups 19, 10, and 29, 20 respectively. This same scheme is carried 90 out until the entire 8,000 numbers beginning with 1 are assigned. The remaining 2,000 numbers begin with 5 and are assigned to the last twenty connector groups 91-00, inclusive, in the same way as the first twenty 95 connector groups 11-20, inclusive, the only difference between the numbers assigned to these two groups being in the first character, which is 1 in one case and 5 in the other. From the above it is thought that the number layout of, not only office No. 1, but also of the remaining offices can be appreciated.

Referring now particularly to Fig. 3, this 100 is a drawing showing the relation between the numbers according to the twenty character system and the actual numbers according to the positions to which they are assigned on the connector switches of the first 100 line group, Fig. 2. In this drawing, each rectangle represents one line or one position on a 105 connector switch, and the number of each line according to the decimal system, or rather the number corresponding to its position in the connector bank is written in the upper portion of the rectangle, while the 110 complete number of each line according to the twenty character system is written along the center of the rectangle. It is seen that the 100 numbers 1—1—1—1 to 1—1—5—20 are assigned in order to the 100 lines 11 to 00, inclusive. The same scheme is carried 115 out in each of the other connector groups.

Referring now particularly to Figs. 4-10, inclusive, Fig. 4 shows the substation A, of which the line comprising conductors 11 and 12 terminates at the exchange in the line switch C. The line switch C has access to the first selector D by way of the trunk with which the trunk circuit TC is associated. The secondary switch SS is associated with 120 125 130

the trunk circuit TC and has access to a plurality of directors of which the one shown in Figs. 5-10, inclusive, is one.

The portion of the director shown in Fig. 5 comprises the controlling relays 101 and 102, and the sequence switches S and S'; the portion of the director shown in Fig. 6 comprises the relays 201-205, inclusive, and the sending switch SEN; the portion of the director shown in Fig. 7 comprises the first character register R-1 and the second character register R-2; the portion of the director shown in Fig. 8 comprises the third character register R-3 and the fourth character register R-4; the portion of the director shown in Fig. 9 comprises the four connecting relays shown; and the portion of the director shown in Fig. 10 comprises the intermediate distributing frame IDF by means of which the conductors associated with the sixteen offices can be cross connected with the conductors of the sender in accordance with the inter-office trunking system.

25 The substation A is an automatic substation of the usual type and has, in addition to its talking and signalling arrangements, a calling device CD for controlling the setting of the register switches of the director. This calling device is designed to produce a maximum of twenty impulses in one series and, while the present invention is not particularly concerned with any special mechanical embodiment, it will be assumed for the purpose of this application that the calling device disclosed and described in the co-pending application of Blessing, S. N. 508,478, filed October 18, 1921, is the one used. This calling device is provided with the digits 1 to 0, inclusive, and, in addition, is provided with the letters A to H, inclusive, and the letters J and K, the letter I being omitted in order to avoid its being confused with the digit 1.

40 The numerical switches of this system, of which the switch D, Fig. 4, is shown, are mechanically of the well known vertical and rotary type in which the bank contacts are arranged in ten horizontal rows or levels.

50 The line switch C, Fig. 4, is mechanically of the rotary type of switch in which the wipers have no normal position and move in a forward direction only. The secondary switch SS is of the same mechanical structure as well as the sequence switch S', and the sender SEN, Figs. 5 and 6, respectively. It may be pointed out also that each of these switches is of the particular type in which the wipers are advanced upon the deenergization rather than upon the energization of the operating magnet.

55 The sequence switch S, Fig. 5, is mechanically a simple switch having the wipers 108-111, inclusive, which are operated step by step in one plane only by the stepping

magnet 103 and which are restored to normal by the release magnet 104, which, in turn, is controlled by the off normal contacts 105. The register switch R-1-R-4, inclusive, Figs. 7 and 8, are mechanically similar to the sequence switch S and differ only as regards the number of wipers employed and as regards the number of steps taken.

The IDF, Fig. 10, is provided for the purpose of permitting the inter-office trunking system to be laid out along the most economical lines, and, accordingly, the conductors 331-346, inclusive, and 351-366, inclusive, from the banks of the wipers 312 and 313, Fig. 7, are brought over and connected up to the right hand side of the IDF in pairs, the first pair on the bottom being associated with office No. 1, the second pair with office No. 2, etc., as indicated by the numerals placed immediately to the left of the terminals.

In order that the detailed operation of the system can be readily understood, it will now be explained how a call is handled. It will be assumed that this call is originated by the subscriber at substation A and is intended for the subscriber whose directory number is 115K (K being the twentieth character on the calling device), and whose number as sent out by the director, after being translated, is 75-1100. The digits 7 and 5, it may be explained, are called the office-digits on account of the fact that they effect the office selection, while the remaining ones are called the subscriber-digits because they effect the selection of the desired subscriber after the call has been trunked to the correct office.

45 When the receiver is removed at substation A, line relay 14 energizes over line conductors 11 and 12. Upon energizing, line relay 14 places ground on private normal conductor 9 at armature 20, thereby making the calling line busy, and closing a circuit for switching relay 13 and stepping magnet 15 in series. As a further result of the energization of line relay 14, it connects test wiper 22 to the junction of switching relay 13 and stepping magnet 15 at armature 19.

50 In case the trunk upon which the wipers of the switch are standing is idle, switching relay 13 energizes immediately. Assuming the trunk to be busy, however, switching relay 13 is short circuited by the ground potential encountered by test wiper 22 on the busy test contact and does not energize, and the wipers are rotated step by step by the buzzer-like action of stepping magnet 15, which is operated through test wiper 22. When an idle trunk is reached, which trunk it will be assumed is the one terminating in bank contacts 24-26, inclusive, switching relay 13, being no longer short circuited, energizes in series with stepping magnet 15.

Stepping magnet 15, however, does not energize at this time on account of the high resistance of switching relay 13. Switching relay 13, upon energizing, opens a point in the test circuit and prepares the holding circuit at armature 17, and at armatures 16 and 18 disconnects line conductors 11 and 12 from the winding of line relay 14 and ground, and extends them by way of wipers 21 and 23, bank contacts 24 and 26, conductors 27 and 29, and armatures 79 and 81 and their resting contacts, to the upper and lower windings of line relay 75 of the trunk circuit TC. Line relay 75 now energizes over the calling subscriber's loop and closes at armature 78 a circuit for line relay 85 of the secondary switch SS. Line relay 85 energizes at this time and places ground on release trunk conductor 28 at armature 88, thereby establishing a holding circuit for switching relay 13 of the line switch C before the slow acting line relay 14 has had time to deenergize.

As a further result of the energization of line relay 85 of the secondary switch SS, it closes at armature 89 a circuit for switching relay 86 and stepping magnet 87 in series, and at armature 90 connects test wiper 97 to the junction of switching relay 86 and stepping magnet 87. The further operation of the secondary switch SS depends upon whether the director upon which it is standing is busy or idle. In case it is busy, release trunk conductor 70 is grounded and the secondary switch operates in the same manner as the line switch C and selects an idle director. It will be assumed in the present case, however, that the director upon which the wipers of the secondary switch are standing is idle, and in that case, no hunting operation takes place and switching relay 86 energizes immediately in series with the low wound stepping magnet 87. As a result of the energization of switching relay 86, ground is placed on release trunk conductor 70 at armature 93. This results in the release relay 201, Fig. 6, becoming energized over conductor 70. The energization of this relay, however, is merely a preparatory operation and does not produce any immediate effect. As a further result of the energization of switching relay 86 of the secondary switch SS, the impulsing circuit for the director is prepared at armature 94, and a bridge is closed across the line conductors 30 and 32 extending to the selector D at armatures 91 and 92. This bridge includes the secondary switch wipers 95 and 96, conductors 68 and 69, resting contact of armature 231 and said armature, Fig. 6, and armatures 210 and 212, and their resting contacts. Line relay 41 of the selector D now energizes over this loop and closes a circuit for release relay 42 at armature 52. Release relay 42, upon energiz-

ing, opens a point in the circuit of release relay 46 and prepares a circuit for vertical magnet 47 at armature 54, and at armature 53 places a ground upon release trunk conductor 31, thereby preparing certain local circuits for relays 44 and 45 and for rotary magnet 48 which will be completed subsequently. The selector D is now ready for operation.

When the subscriber at substation A operates his calling device CD in accordance with the first character (the digit 1) in the desired number, one interruption is produced in the circuit of line relay 75. Relay 75 thereupon deenergizes once momentarily, and at armature 77 places ground on the impulse lead 71 of the director. This results in an impulse of current being transmitted to the operating magnet 301 of the register R-1, Fig. 7, by way of the slow acting series relay 101, Fig. 5, the impulse distributing wiper 111 of the sequence switch S, and conductor 112. Upon energizing in response to this impulse of current, operating magnet 301 advances the wipers 311-313, inclusive, into engagement with the first set of associated bank contacts. Series relay 101 is energized at this time, and closes a circuit for the slow acting relay 102 at armature 106. Relay 102, accordingly, energizes and prepares a circuit for the operating magnet 103 of the sequence switch S at armature 107. Then when relay 101 deenergizes upon the termination of the impulse of current sent through it, it opens the circuit of the slow acting relay 102 and completes the circuit of the stepping magnet 103. Relay 102 is slow acting, and for that reason maintains armature 107 attracted sufficiently long to permit the magnet 103 to be operated after which it deenergizes and opens the circuit of magnet 103. By the operation of magnet 103 the wipers 108-111, inclusive, of the sequence switch S, are advanced into engagement with the second set of bank contacts. Wiper 111, it will be noted, shifts the impulse lead from conductor 112 to conductor 113.

When the calling subscriber manipulates his calling device CD in accordance with the second character (the digit 1) in the desired number, line relay 75 of the trunk circuit TC responds by sending an impulse of current over the impulse lead 71 and through the series relay 101, Fig. 5. Since wiper 111 is at this time in engagement with conductor 113, the stepping magnet 304 of the second digit register R-2 is at this time operated, and accordingly the wipers 321-326, inclusive, of the register R-2, are moved into engagement with the first set of bank contacts.

Upon the termination of this impulse the wipers of the sequence switch S are advanced another step in the manner described

above, thereby shifting the impulse lead at wiper 111 into engagement with conductor 114 extending to the operating magnet 401 of the register R-3.

- 5 Since the first two characters in the desired number have been registered, and since it never requires more than two characters to determine the desired office, the sending equipment may now be permitted to operate 10 to bring about the selection of the desired office. The operation of the sending equipment is initiated at this time upon the wiper 108 coming into engagement with the third associated bank contact and thereby grounding the conductor 141. The description of 15 the operation of the sending equipment, however, will be deferred until the description of the setting of the register switches has been completed.
- 20 When the calling device CD at the substation A is operated in accordance with the third character (the digit 5) in the desired number, line relay 75 of the trunk circuit TC is deenergized five times momentarily, and 25 upon each deenergization sends an impulse of current over the operating circuit through the series relay 101 and wiper 111 (now in engagement with the third bank contact), to the stepping magnet 401 of the third register R-3, by way of conductor 114. By the 30 operation of stepping magnet 401, the wipers 411-417, inclusive, of the register R-3 are advanced step by step into engagement with the fifth set of bank contacts. Series relay 35 101 is energized as usual upon the first impulse being transmitted through it, and being slow acting maintains its armature 106 attracted throughout the series of impulses, and when relay 101 deenergizes upon the 40 termination of the series of impulses, stepping magnet 103 is again operated and the wipers 108-111, inclusive, of the sequence switch S are advanced into engagement with the fourth set of bank contacts.
- 45 When the calling subscriber manipulates his calling device CD in accordance with the fourth character (the letter K) in the desired number, line relay 75 responds by momentarily deenergizing twenty times. This 50 results in twenty impulses of current being sent over the operating circuit and through series relay 101 to the wiper 111, and thence by way of the fourth contact in the bank of wiper 111 and conductor 115 to the stepping 55 magnet 404 of the fourth register switch R-4. Stepping magnet 404 responds and advances the wipers 421 and 422 into engagement with the twentieth set of their associated bank contacts.
- 60 The operation of the sending equipment will now be taken up and explained. Since the first character in the number called is the digit 1, the called subscriber's line terminates in office No. 1 as can be seen by referring to Fig. 1. It will be assumed that

the inter-office trunking system is such that, in order for a call to be trunked from the office in which the line of substation A terminates to office No. 1, two digits must be sent out by the sending equipment. It will be 70 assumed that these digits are 7 and 5, respectively. Accordingly, the first and second digit stop conductors 351 and 331, respectively, Fig. 10, of office No. 1, are connected at the intermediate distributing frame IDF 75 by means of the jumpers 401 and 402 to the seventh and fifth impulse stop conductors, respectively. With these facts in mind, the subsequent operations may now be appreciated. 80

As pointed out hereinbefore, when wiper 108 of the sequence switch S, Fig. 5, arrives upon the third associated bank contact at the end of the registration of the second character in the called number, it places 85 ground on conductor 141. This results in ground being placed on start conductor 139 through the first contact in the bank of wiper 134 of the sequence switch S' and said wiper. When this occurs, a circuit is closed 90 over start conductor 139 for sending relay 202 including armature 216 and its resting contact, armature 219 and its resting contact, and the constantly operating interrupter 221. Relay 202, accordingly, starts 95 to energize and deenergize under the control of interrupter 221, and upon its first effective energization a circuit is closed at armature 211 for stepping magnet 222 of the sending switch SEN. Stepping magnet 222 100 thereupon energizes and moves the associated pawl into engagement with the next notch in the associated wiper driving ratchet wheel. This does not move the wipers on the switch. 105

Upon the next deenergization of sending relay 202, the circuit of stepping magnet 222 is opened at armature 211, whereupon magnet 222 deenergizes and permits the wipers 224 and 225 to be advanced in a clockwise direction into engagement with the first set of associated bank contacts. Wiper 225, upon engaging its second bank contact, completes a circuit for pick-up relay 203. Pick-up relay 203 now energizes and prepares a locking circuit for stop relay 204 at armature 214, and at armature 213 closes a circuit from ground through the resting contact of armature 215 and said armature and over conductor 138 for stepping magnet 131 115 of the sequence switch S'. Upon energizing, stepping magnet 131 moves the associated pawl into engagement with the next notch in the wiper driving ratchet wheel, but does not move the wipers of the switch. As a 120 further result of the energization of pick-up relay 203, Fig. 6, it removes at armature 212 the shunt from around armature 210 of sending relay 202 and its resting contact, thereby leaving the bridge across the talking 125 130

conductors extending to the selector D, Fig. 4, under the control of the sending relay at armature 210.

Accordingly, upon the next energization 5 of relay 202, an interruption is produced in the outgoing control circuit at armature 210 in addition to the closure of the circuit of stepping magnet 222 at armature 211. Upon the following deenergization of sending relay 202, the outgoing control circuit is again closed at armature 210 and the circuit of stepping relay 222 is again opened at armature 211, whereupon the switch wipers 224 and 225 are advanced into engagement with 10 the second set of associated bank contacts. This brings wiper 224 into engagement with the contact in which the first stop conductor is terminated. This stop conductor is not connected up to ground at this time, 15 however, and accordingly this is without effect.

The operation of the sending relay 202 and the sender SEN continues as described until seven interruptions have been produced at 20 armature 210 in the outgoing control circuit. The seventh interruption is produced while the wiper 224 is on the seventh associated bank contact, and upon its termination by relay 202, the wiper 224 is advanced into engagement with the eighth associated bank contact thereby closing a circuit for stop relay 204 as follows: From ground by way of the stop conductor control wiper 135 of sequence switch S', Fig. 5, the first associated bank contact, the first office-digit stop conductor 151, wiper 313 of the first register switch R-1, the first associated bank contact, conductor 351, jumper 401 of the intermediate distributing frame IDF, Fig. 10, 25 the seventh impulse stop conductor, the associated contact in the bank of wiper 224 of the sending switch SEN, Fig. 6, wiper 224, and stop relay 204 to battery. Stop relay 204, upon energizing over this circuit, completes a locking circuit for itself at armature 217; disconnects sending relay 202 at armature 216 while the said relay 202 is still in a deenergized condition; and at armature 215 opens the circuit of stepping magnet 30 131 of the sequence switch S', whereupon the wipers 133-135, inclusive, are advanced into engagement with the second set of bank contacts. Wiper 135, it will be noted, removes ground from the first office-digit stop conductor 151 and places it upon the second office-digit stop conductor 152.

In the sending equipment, Fig. 6, as a 35 still further result of the energization of stop relay 204, it connects the stepping magnet 222 to wiper 225 at armature 218, whereupon the wipers 224 and 225 are rapidly spun around to their normal position owing to the buzzer-like action of stepping magnet 222 which interrupts its own circuit at contacts 40 223. When wiper 225 passes off the last

grounded band contact the automatic operation of magnet 222 ceases and the circuit of pick-up relay 203 is opened. Pick-up relay 203, however, is slow acting and does not fall back immediately.

Before the operation of the sending equipment is described further, the operation of the selector D will be described. It will be remembered that the circuit of line relay 41 of the selector D was opened seven times momentarily at armature 210 of sending relay 202 during the travel of the wipers of the sending switch SEN under the control of the said sending relay 202. Line relay 41 of the selector D, accordingly, deenergizes in response to each of the seven interruptions produced in its circuit, and closes at armature 52 a circuit for vertical magnet 47 as follows: From ground by way of the resting contact of armature 60 and said armature, armature 52 and its resting contact, armature 54 and its working contact, slow acting series relay 43, and vertical magnet 47 to battery. By the operation of vertical magnet 47 the wipers 62-64, inclusive, of the selector D are raised step by step and come to rest opposite the seventh level of bank contacts. Relay 43 is energized in series with vertical magnet 47, and being slow acting maintains its armature 55 attracted throughout the vertical movement. Upon the closure of off normal contacts 51, which occurs at the end of the first vertical step, a circuit is closed for stepping relay 44 as follows: From ground by way of the working contact of armature 53 and said armature, armature 55 and its working contact, off normal contacts 51, interrupter contacts 50, and stepping relay 44 to battery. Stepping relay 44, upon energizing, closes a locking circuit for itself at armature 56, and at armature 57 prepares a circuit for rotary magnet 48.

At the end of the vertical movement, slow acting series relay 43 deenergizes and completes the circuit of rotary magnet 48. Rotary magnet 48 thereupon energizes and advances the wipers 62-64, inclusive, into engagement with the first set of contacts in the selected level, and (near the end of its stroke opens the circuit of stepping relay 44 at interrupter contacts 50. Stepping relay 44, upon deenergizing, opens the circuit of rotary magnet 48 at armature 57, whereupon rotary magnet 48 deenergizes and closes its interrupter contacts again.

The further operation of the selector D now depends upon whether the trunk terminating in the first set of bank contacts in the selected level is busy or idle. If it is 125 idle, switching relay 45 energizes immediately in series with stepping relay 44. Assuming it to be busy, however, switching relay 45 is short circuited by the ground potential encountered on the busy test contact 130

5 by test wiper 63, and stepping relay 44 energizes through the test wiper 63 and again closes the circuit of rotary magnet 48 at armature 57, whereupon the wipers of the
 10 switch are advanced into engagement with the second set of bank contacts. This alternate operation of the stepping relay and the rotary magnet continues as described until an idle trunk is reached, which trunk, it will
 15 be assumed, is the one terminating in bank contacts 65-67, inclusive. When this occurs, switching relay 45 is no longer short circuited and energizes in series with stepping relay 44. Stepping relay 44, however, does
 20 not energize at this time owing to the high resistance of switching relay 45. Upon energizing, switching relay 45 disconnects ground from armature 52 of line relay 41 at armature 60, thereby opening the circuit
 25 of slow acting release relay 42; disconnects test wiper 63 from the junction of switching relay 45 and stepping relay 44 and connects it to the grounded release trunk conductor 28 at armature 59, thereby making the seized trunk busy immediately; and at armatures 58 and 61 disconnects the line conductors from the windings of line relay 41 and extends them by way of the working contacts of armatures 58 and 61, wipers 62
 30 and 64, and bank contacts 65 and 67 to the line relay of the selector switch to which the seized trunk extends.

35 The line and release relays of the seized selector switch now energizes in the usual manner and the latter places a ground potential on the associated release trunk conductor, thereby closing a holding circuit for the switching relay 45 through test contact 66, test wiper 63, and armature 59 and its
 40 working contact. This ground potential extends back over release trunk conductor 28 to the switching relay 13 of the line switch C and maintains that relay energized. It will be understood, of course, that this
 45 ground potential is applied to the release trunk conductor by the seized selector switch before the slow acting release relay 42 of the selector D has had time to deenergize.

50 Returning now to the sending equipment of the director, the slow acting pick-up relay 203 deenergizes after an interval and opens the circuit of the slow acting stop relay 204 at armature 214. Slow acting stop relay 204 also deenergizes after an interval, 55 and again connects up the sending relay 202 at armature 216. The interval required for the slow acting relays 203 and 204 to fall back one after the other is utilized as above described by the selector D in changing over and selecting a trunk after the vertical movement has been effected.

55 Sending relays 202 now starts to vibrate again under the control of the interrupter 221, with the result that the sending switch 60 SEN is operated as before to count off the

number of interruptions that are produced in the outgoing control circuit at armature 210. This second series of interruptions, representing the second office-digit, comprises five interruptions and is terminated 70 when stop relay 204 energizes over the following circuit: From ground by way of the stop conductor control wiper 135 of the sequence switch S', the second associated bank contact, the second office-digit stop conductor 152, wiper 312 of the register switch R-1, Fig. 7, the first associated bank contact, conductor 331, jumper 402 of the intermediate distributing frame IDF, the fifth impulse stop conductor, and thence to battery through wiper 224 of the sending switch SEN and stop relay 204. Upon the energization of stop relay 204 the wipers of the sequence switch S' are advanced one step in the manner described above, and the wipers of the sending switch SEN are again spun around to their normal position, after which the slow acting relays 203 and 204 fall back one after the other to start the sending out 80 of the first digit in the desired subscriber's 85 number.

90 In response to the five interruptions produced in the outgoing control circuit in accordance with the second office-digit 5, the selector switch which was seized as above 95 described by the selector D, Fig. 4, raises its wipers to the fifth level and selects an idle trunk extending to a thousands selector in office No. 1.

100 The sending relay 202 now starts to operate under the control of interrupter 221, with the result that the sending switch SEN is stepped around to count off the interruptions produced in the outgoing control circuit. The first digit in the subscriber's 105 number as translated is 1, and accordingly stop relay 204 is energized at the termination of the first impulse produced in the outgoing control circuit. Relay 204 is energized at this time over the following circuit: 110 From ground by way of stop conductor control wiper 135 of the sequence switch S', the first subscribed-digit stop conductor 161, wiper 311 of the first register switch R-1, 115 the first associated bank contact, conductor 425, wiper 411 of the third register switch R-3, the fifth associated bank contact, conductor 427, wiper 321 of the second register switch R-2, the first associated bank contact, the first impulse stop conductor, and thence to battery by way of wiper 224 of the sending switch SEN and stop relay 204.

120 This one interruption produced in the outgoing control circuit causes the thousands selector to which the connection has been 125 extended to raise its wipers opposite the first level of bank contacts and select an idle hundreds selector in the first thousand of office No. 1.

130 After the usual interval brought about by

- the slowness of relays 203 and 204, Fig. 6, the sending equipment starts operating again for the second or hundreds digit 1 in the subscriber's number. It will be understood, of course, that the sequence switch S' was advanced one step as usual in response to the sending out of the first digit 1, and that the wipers thereof are now in engagement with the fourth set of bank contacts. 5
- 10 That being the case, stop relay 204 is energized following the termination of the first interruption in the outgoing control circuit over a circuit which is as follows: From ground by way of the stop conductor control wiper 135, the second subscriber-digit stop conductor 162, wiper 324 of the second register switch R-2, the first associated bank contact, conductor 429, wiper 415 of the third register R-3, the fifth associated bank 15 contact, and thence by way of the first impulse stop conductor to battery through wiper 324 of the sending switch SEN and stop relay 204.
- 15 In the exchange No. 1, the hundreds selector to which the connection has been extended raises its wipers to the first level in response to the sending out of the above digit, and selects an idle connector switch in the first hundred of the first thousand lines. 20
- 20 The sequence switch S' is automatically advanced another step and the sending equipment again starts to operate. The third digit in the called subscriber's number is 0, and accordingly at the end of the tenth 25 interruption produced in the outgoing control circuit stop relay 204 is again energized in response to wiper 224 of the sending switch SEN arriving upon the tenth impulse stop conductor. The circuit of stop relay 204 at this time is as follows: From ground by way of the stop conductor control wiper 135 of the sequence switch S', the fifth associated bank contact, the third subscriber-digit stop conductor 163, wiper 421 30 of the fourth register switch R-4, the twentieth associated bank contact, conductor 432, wipers 413 of the third register R-3, the fifth associated bank contact, and thence to battery by way of the tenth impulse stop conductor, wiper 224 of the sending switch SEN, and stop relay 204. The sequence switch S' is automatically advanced one step 35 at this time and arrives on the sixth set of bank contacts. 40
- 45 In the office No. 1, the connector switch to which the connection has been extended raises its wipers opposite the tenth level of bank contacts in response to the sending out of the third digit 0 in the desired subscriber's number. 50
- 55 The sending switch SEN is again started and this time counts off the interruptions produced in the outgoing control circuit in accordance with the fourth digit 0 in the desired subscriber's number, and upon wiper 60
- 65 224 coming into engagement with the contact in which the tenth impulse stop conductor terminates, stop relay 204 is energized over the following circuit: From ground by way of the stop conductor control wiper 135, the fourth subscriber-digit stop conductor 164, wiper 422, the twentieth associated bank contact, and thence to battery by way of the tenth impulse stop conductor, wiper 224 of the sending switch SEN, and stop relay 204. 70
- 75 The sequence switch S' is now advanced another step, and its wipers come into engagement with the seventh set of associated bank contacts with results which will be pointed out hereinafter. 80
- 85 In the office No. 1, the connector switch to which the connection has been extended rotates its wipers in response to the fourth and last digit 0 in the desired subscriber's number into engagement with the tenth set of bank contacts in the tenth level, and starts to ring the desired subscriber's bell. 90
- 95 In the director, wiper 135 of the sequence switch S' upon coming into engagement with the seventh associated bank contact as pointed out above, places ground on the incoming impulse conductor 71, thereby closing a circuit over the said impulse conductor for switching relay 76 of the trunk circuit TC. This circuit includes armature 77 and its working contact of line relay 75, and the normally closed contacts controlled by armature 80. Switching relay 76, upon energizing, locks itself to the grounded release trunk conductor 28 and opens its initial circuit at armature 80; connects release trunk conductors 31 and 28 together at armature 83; and at armature 79 and 81 disconnects line conductors 27 and 29 from the windings of line relay 75 and extends them to the corresponding conductors 30 and 32 of the selector D, at the same time disconnecting the said conductors 30 and 32 of the selector D from the control circuit coming from the director. The connection is now under the direct control of the calling subscriber. Line relay 75, upon deenergizing in response to being disconnected, opens the circuit of relay 85 at armature 78, whereupon relay 85 deenergizes after the interval for which it is adjusted and opens the circuit of switching relay 86. Switching relay 86 now deenergizes and disconnects its wipers, thereby freeing the director and removing ground from conductor 70. 100
- 105 In the director, when ground is removed from the release trunk conductor 70, release relay 201 deenergizes and places ground on the common release conductor 140 at armature 209, thereby closing a circuit which includes release magnet 104 of the sequence switch S, release magnet 302 of the first register switch R-1, release magnet 305 of the second register switch R-2, release magnet 402 of the third register switch 110 120
- 125 130

R—3, and release magnet 405 of the fourth register switch R—4. These release magnets accordingly energize and restore their respective switches to normal position, and 5 their circuits are opened by their respective associated off normal contacts when the associated wipers reach their normal positions. It may be pointed out that the circuit of release magnet 104 of the sequence switch 10 S is opened at off normal contacts 105, and that the circuits of release magnets 302, 305, 402 and 405 of the registers R—1—R—4, inclusive, are opened at off normal contacts 303, 306, 403 and 406, respectively.

15 As a further result of the deenergization of release relay 201, Fig. 6, it closes at armature 206 a restoring circuit for stepping magnet 131 of the sequence switch S'. This circuit includes the conductor 136, wiper 133, 20 and interrupter contacts 132 of the stepping magnet 131. Accordingly, the stepping magnet 131 operates in a buzzer-like manner and advances the wipers 133—135 to their normal position.

25 As a still further result of the deenergization of release relay 201, it places a shunt around armature 218 and its working contact of stop relay 204 at armature 208, thereby connecting wiper 225 with the stepping magnet 222 through the interrupter 223. This is the usual restoring circuit for the stepping magnet 222, but it is not effective at this time since the wipers are already 30 in a normal position. This circuit, it may 35 be pointed out, is brought into play, however, when the calling subscriber hangs up and brings about the release of the director while the sending switch is off normal.

The director is now completely restored 40 to normal and is ready to be used in a subsequent call.

Returning now to the established connection, when the called subscriber responds, the ringing current is cut off in the usual 45 manner and conversation may take place, and when the conversation is terminated and the calling subscriber replaces his receiver, the connector switch in use is released in the usual manner and removes ground from the 50 associated release trunk conductor, thereby permitting the various selectors included in the connection, of which the selector D, Fig. 4, is one, to release. The release of the selector D, it may be pointed out, is brought 55 about upon the deenergization of switching relay 45, which closes at armature 60 a circuit for release magnet 46 through armatures 52 and 54, and off normal contacts 49. The circuit of release magnet 46 is again 60 opened at off normal contacts 49 by the switch shaft when the latter reaches normal position. The circuits at the line switch C and the trunk circuit TC assume normal condition upon the deenergization of the 65 relays 13 and 76. The entire connection is now

released and the apparatus used therein is ready to be used in a subsequent call.

Referring now particularly to Figs. 1-3, inclusive, and to Figs. 7-10, inclusive, it will now be explained more in detail just how 70 the numbers received by the director are translated in accordance with the number assignment indicated in Figs. 1-3, inclusive. It is obvious that the wipers 313 and 312 of the first register R—1, Fig. 7, connect up 75 the first and second office-digit stop conductors 151 and 152, respectively, to the desired set of terminals on the right hand side of the intermediate distributing frame, IDF, Fig. 10, when the first character in the 80 number is not 5 or divisible by 5, as in that case the first character alone determines the office to which the call is going. In case the first character is 5, or divisible by 5, that character does not determine definitely the 85 office to which the call is going. This can be readily seen by referring to the system layout shown on Fig. 1, which plainly shows, by means of the lower formulas written inside the various rectangles, that when the 90 character 5 is the first character, the call may be intended for either of the first four offices. Similarly, if the first character is divisible by 5, such as 10, 15, or 20, the call may be for any one of four different offices. 95 Accordingly, the office cannot be determined in such a case until the second character in the number is received. Assuming a case in which the first character is 5, then if the second character is anything from 1 to 5, inclusive, the call is meant for a line which terminates in office No. 1, while if the second character is anything from 6-10, inclusive, the call is meant for a line which terminates in office No. 2, etc. Accordingly, when 100 the first character is 5, or divisible by 5, the wipers 313 and 312 are stopped on contacts which are not connected with the IDF. Then, when ground is placed on start conductor 139, Fig. 5, at the end of the operation of the second register R—2, as described hereinbefore, a circuit is closed over the stop conductor control wiper 135, the first digit stop conductor 151, wiper 313 of the first 110 register R—1, the bank contact with which it is in engagement, (say the fifth), conductor 371, normally closed contacts controlled by armature 305, and relay 301 to battery. Relay 301, upon energizing, locks itself to conductor 70 and opens its initial circuit at 115 armature 305, and at its four left hand armatures connects the four conductors 381-384, inclusive, coming from the bank of wiper 325 of the second register R—2, to the conductors 351-354, inclusive, extending to the 120 lower terminals of the first four sets on the right hand side of the IDF. As a further result of the energization of relay 301, it connects at its four right hand armatures, the four conductors 391-394, inclusive, coming 125

from the bank of wiper 326 of the second register R-2, to the four conductors 331-334, inclusive, which are connected to the upper terminals of the first four sets on the right hand side of the IDF. With these conductors so connected, since the first and second office-digit stop conductors 351 and 352 are connected to the wipers 325 and 326, respectively, of the second register R-2, the first and second office-digit stop conductors are extended through to the corresponding terminals of one of the first four offices on the right hand side of the IDF, depending, of course, upon the second character in the number received.

In case the register R-1 is set upon the tenth set of contacts, relay 302, instead of 301, is operated over conductor 372 and connects the conductors coming from the banks 20 of wipers 325 and 326 to the conductors 335 to 338 and conductors 355 to 358, inclusive, associated with the offices 6-9, inclusive.

Similarly, if the wipers of the register R-1 are set on the fifteenth set of bank contacts, relay 303 is operated over conductor 373 and connects the conductors 381-384, inclusive, and 391-394, inclusive, to the conductors 369-362, inclusive, and 339-342, inclusive, respectively, which are associated with the offices 11-14, inclusive.

It may also be seen that if the wipers of the register R-1 are set upon the twentieth set of bank contacts, the relay 304 is operated over conductor 374 and connects the conductors coming from the banks of the wipers 325 and 326 to the conductors 343-346, inclusive, and 363-366, inclusive, which extend to the contacts on the right hand side of the intermediate distributing frame IDF 40 that are associated with the offices 16-19, inclusive.

From the foregoing it may be seen how the registers R-1 and R-2 and the relays 301-304, inclusive, co-operate to connect the first and second office-digit stop conductors to the correct set of terminals on the right hand side of the IDF, so that the call may be trunked to the desired office. Accordingly, it will now be explained how the selection of the correct thousand is effected.

The selection of the correct thousands digit is accomplished by two different sets of wipers. One set comprises wiper 311 of the first register R-1, wiper 323 of the second register R-2, and wiper 414 of the third register R-3. This is the set of wipers used when the first register R-1 is set upon the fifth, tenth, fifteenth or twentieth set of bank contacts, in which case the wiper 55 311 of the register R-1 extends the first subscriber-digit stop conductor 161 to wiper 323. The wiper 323, as well as the wiper 414, has to choose between only two digits 9 and 0. This can be understood best by referring to Fig. 2, in which it will be noted

that the first 8000 lines of office No. 1 have a common first character, which is the digit 1, and that the remaining 2000 lines have the first character 5. It is therefore evident that if the first character in the number is 5, and if it is determined that the call is intended for office No. 1, that the thousands digit must be either 9 or 0, because all the numbers in office No. 1 beginning with the character 5 are in the ninth and tenth thousands. The same rule applies to the remaining offices. It will be noted that if the second character in the number is 1 or 2, the number belongs to the ninth thousand, while if the second character is 3 or 4, the number 80 belongs to the tenth thousand. Accordingly, the first and second contacts in the bank or wiper 323, Fig. 7, are connected to the ninth impulse stop conductor, and the third and fourth contacts are connected to the tenth impulse stop conductor. It will be noted further that if the second character in the number is 5, the number may be in either the ninth or tenth thousand, depending upon whether the third character is from 1-10, inclusive, or from 11-20, inclusive. Accordingly, the fifth contact in the bank of wiper 323 is connected through conductor 428 to wiper 414 of the third register switch R-3, and the first ten contacts in the bank of wiper 414 are connected to the ninth impulse stop conductor, while the remaining ten are connected to the tenth impulse stop conductor. The remaining contacts in the bank of wiper 323 are similarly connected up.

It will be noted that if wiper 311 of the first register switch R-1 stops on any of the bank contacts other than the fifth, tenth, fifteenth, or twentieth, the first subscriber-digit stop conductor 161 is connected through conductor 425 to wiper 411 of the third register switch R-3. The contacts in the bank of wiper 411 are, in turn, connected through conductors 426 and 427 to the wipers 321 and 322 of the second register switch R-2. The bank contacts of the wipers 321 and 322 are both connected up in the same way except as regards the fifth, tenth, fifteenth and twentieth sets. Accordingly, in case the setting of the register R-1 indicates that the number is assigned to one of the first 8000 lines in an office, the office No. 1 for example, and in case the second register R-2 is set on a set of contacts other than the fifth, tenth, fifteenth or twentieth, the setting of wiper 411 of register switch R-3 does not produce any change in the thousands digit owing to the fact pointed out above, that the banks of wipers 321 and 322 are wired both exactly the same except as regards the contacts 5, 10, 15 and 20.

Referring now particularly to Fig. 2, it will be noted that if the first character in the number is 1, (resulting in the call being 130

trunked to office No. 1), and if the second character in the number is 1 or 2, the number belongs to the first thousand, while if the second character in the number is 3 or 4, the 5 number belongs to the second thousand. Accordingly, the first and second contacts in the banks of the wipers 321 and 322 are connected to the first impulse stop conductor, and the third and fourth are connected to 10 the second impulse stop conductor. It may be noted further that if the first character in the number is 1, and the second character in the number is 5, the number may belong to either the first or the second thousand 15 lines in office No. 1, depending upon whether the third character in the number is from 1-10, or from 11-20. This choice is made by wiper 411 of the third register R-3, which connects up wiper 321 in case it is set 20 on one of the first ten contacts, and connects up wiper 322 in case it is set on one of the remaining ten contacts. The fifth contact in the bank of wiper 321 is connected with the first impulse stop conductor so as to direct 25 the call to the first thousand in case that wiper is the one connected up by wiper 411, while the fifth contact in the bank of wiper 322 is connected to the second impulse stop conductor so as to direct the call to the second 30 thousand in case the wiper 322 is the one connected up by wiper 411. The same thing holds true as regards the remaining digits on which a choice must be made by the wipers 321 and 322, assisted by the wiper 411. 35 Referring now to Fig. 2, and more particularly to the first thousand lines, it will be noted that if the second character is 1, the call may be for either one of the first 400 lines in that thousand, while if the second 40 character is the digit 2, the call may be for either one of the second 400 lines in that thousand. Accordingly, the wiper 324 of the second register R-2, Fig. 7, connects the second subscriber-digit stop conductor 45 162 to wiper 415 of the third register R-3, (which has access to the first four stop conductors), in case the register R-2 is set on the first set of contacts, while the wiper 324 connects the second subscriber-digit stop conductor 50 162 to the wiper 416, (which has access to the fifth, sixth, seventh and eighth stop conductors), in case the register R-2 is set upon the second set of bank contacts. It will be noted also, in reference to the second 55 thousand lines of office No. 1, Fig. 2 that the assignment of numbers in this thousand is the same as in the first thousand as regards the first 800 lines with the exception that the second characters are 3 instead of 1 and 4 instead of 2. Accordingly, the first and third contacts in the bank of wiper 324, Fig. 7, are multiplied together as well as the second and fourth. The fifth contact, however, is not connected with either of the first 60 four, but is connected through conductor 65

431 to wiper 417, which has access to the stop conductors 9 and 0. This is done in order to discriminate between the digits 9 and 0 when the second character is 5, the block of numbers of which the third character 70 may be from 1-5 being assigned to the ninth hundred in the first thousand, while the block of numbers whose second character may be from 6-10 being assigned to the tenth hundred in the first thousand. The remaining 75 ten contacts in the bank of wiper 417, Fig. 8, discriminate between the digits 9 and 0 when the third character is above 10, in which case the number is assigned to either the ninth or tenth hundred in the second thousand. 80

The second digit in the number is determined in the same way for the remaining 8000 lines.

Referring now particularly to Fig. 3, which is a detailed layout of the first one 85 hundred numbers in office No. 1, the manner in which the third subscriber-digit is determined will be explained with reference thereto. Since the first two characters in each of these numbers as called are the same, 90 it will be necessary to consider only the third and fourth characters. It will be noted that the third character of the first twenty numbers is 1, and that the third character of the second twenty numbers is 2, etc. Accordingly, additional means must be provided to determine whether the number called is in the first ten or the second ten when the third character is 1. Accordingly, the third or ten selecting subscriber-digit is determined by the register switches R-3 and R-4. The third subscriber-digit stop conductor 163 extends to wiper 421 of the fourth register switch R-4, which wiper extends it through either the first or the second half 105 of its bank contacts to either the wiper 412 or the wiper 413 of the third register switch R-3. Accordingly, if the first and second characters in the number indicate that the called subscriber's number is found in the 110 group shown in Fig. 3, and if the third character in the number is the digit 1, the wipers 412 and 413 of the third register R-3 are moved into engagement with the first set of associated bank contacts. The wiper 412 115 makes connection with the first impulse stop conductor, and the wiper 413 makes connection with the second impulse stop conductor. Then, in order to completely determine the tens digit, it is only necessary for the wiper 421 of the fourth register R-4 to make a 120 selection between the wipers 412 and 413. Accordingly, if the wiper 421 stops on one of the bank contacts in the first half, the number is assigned to the first ten, while if it 125 stops in the second half of its bank, wiper 413 is connected up on account of the fact that the number is assigned to the second ten. The same arrangement is carried out 130 for the remaining numbers in this one hun-

dred lines, and also for each of the other hundred lines in the system, the only difference being that the three characters of the numbers assigned to the various other hundred line groups may include the characters 6-10, 11-15, or 16-20, inclusive, instead of 1-5, inclusive, as is the case with the group shown in Fig. 3.

It now remains to explain how the fourth 10 or units selecting subscriber-digit is sent out. This digit is determined wholly by the wiper 422 of the fourth register switch R-4. Upon referring to Fig. 3, it will be noted that the last character in each number as 15 called corresponds with the last numeral applied to the corresponding rectangles in the bottom row. Accordingly, the first ten contacts in the bank of wiper 422 are connected to the ten stop conductors in order, thereby 20 giving the correct units selecting digit. It will be noted also, that the last character of each number as called in the second row from the bottom, Fig. 3, run in order from 11-20, and correspond to the digits 1-0. That being the case, the second ten contacts 25 in the bank of wiper 422 are multiplied with the first ten contacts, respectively.

Referring now particularly to Fig. 10, it 30 will be noted that in addition to the ten impulse stop conductor terminals appearing on the left hand side of the IDF, there is an extra terminal marked X. This terminal is assumed to be connected with the corresponding terminal X associated with the second contact in the bank of wiper 133 of 35 the sequence switch S', Fig. 5. This terminal is used in case it is necessary to operate only the selector D to select the desired office. It will be understood that some of 40 the levels of the selector D lead directly to certain of the offices of the system. Assuming that the fourth office is reached by way of a group of trunks accessible to the selector D on the second level, the first contact in 45 the fourth pair on the right hand side of the IDF is connected to the second impulse stop conductor in order to cause the selector D to be stopped at the second level when that office is called, and in order to cause 50 the sequence switch S to pass up its second position and move directly into the correct position for sending out the first subscriber-digit, the second terminal of the pair in question is connected to the terminal X with the 55 result that a circuit is closed for the magnet of sequence switch S' when ground is placed on the second office-digit impulse stop conductor. This causes the magnet of the sequence switch S' to advance the switch automatically from that position to the next. 60 This is the usual expedient made use of in director systems, and is fully explained in the Nelson application hereinbefore referred to.

There is a further feature of the invention

which has not been dwelt on heretofore, and which is not limited to any particular kind of director, and is also applicable equally well to various other types of switches or switching mechanisms that employ sending equipment similar to that employed in the director shown in this application. This feature has to do with sending in an alarm and releasing the partly established connection in case the director fails to send out the 75 correct number.

As has been explained hereinbefore, the sending switch SEN, Fig. 6, counts off the interruptions that are being produced in the outgoing control circuit by sending relay 80 202 at armature 210, and closes a circuit for stop relay 204 at wiper 224 to terminate the digit being sent out when the desired number of interruptions has been produced, at which time wiper 224 encounters a bank contact connected with a grounded impulse stop conductor. It may happen occasionally that a wiper of one of the register switches shown in Figs. 7 and 8 gets out of adjustment and does not make connection with the contact 90 on which it is standing. When that is the case, if the circuit of stop relay 204 includes the wiper in question, the stop relay 204 is not energized when wiper 224 arrives upon the bank contact which would otherwise be grounded, and accordingly the sending mechanism continues to operate until wiper 224 finally comes into engagement with the bank contact in which the tenth impulse stop conductor terminates, or, as an alternative, it may be the tenth impulse stop conductor itself that is supposed to be grounded at this time but it is not grounded due to some cause, such as, for example, a badly adjusted wiper as assumed above. In 105 any case, if the wiper 224 arrives upon the bank contact in which the tenth impulse stop conductor terminates without stop relay 204 having already been energized and locked up, or without the tenth impulse stop 110 conductor having been grounded, a circuit is closed for the alarm relay 205 in series with stop relay 204, whereupon stop relay 204 energizes and terminates the digit being sent out in the usual manner. Relay 205 is 115 also energized and disconnects sending relay 202 at armature 219 so as to prevent any further operation of the sending mechanism until the trouble has been taken care of. As a further result of the energization of relay 120 205, it closes a locking circuit for its lower winding at armature 220. This locking circuit includes the individual lamp 226, the common push button P, and the alarm relay 227. Relay 227, upon energizing, closes at 125 armature 228 a circuit for the alarm buzzer 229, which buzzer accordingly operates to attract the attention of an attendant who may look up the trouble. As a still further result of the energization of relay 205, it 130

5 opens the outgoing control circuit at armature 231, thereby releasing the partly established connection. At armature 231 relay 205 also connects the lead from the busy signal machine B to conductor 69 by way of armatures 210 and 212 in multiple. This results in the tone current being transmitted to the substation A through condenser 82 associated with the trunk circuit TC, and 10 thence over the lower heavy talking conductor.

The calling subscriber upon hearing this busy tone is informed that he cannot obtain the desired connection for the time being, 15 so he hangs up his receiver and calls later. When the receiver is replaced, line relay 75 falls back and opens the circuit of relay 85 of the secondary switch SS which deenergizes soon after and removes ground from 20 release trunk conductor 28 at armature 88, thereby permitting relay 13 of the line switch to deenergize. As a further result of the deenergization of relay 85 of the secondary switch SS, it opens the circuit of 25 switching relay 86 at armature 89, whereupon switching relay 86 deenergizes and disconnects the wipers, thereby removing ground at that point from release trunk conductor 70 of the director. Release conductor 30 70, however, is held grounded in the direction at armature 232 by relay 205 so as to maintain the director non-selectable for the time being to the other secondary switches having access to it.

35 When the calling subscriber again calls he gets another director owing to the fact that this one is made busy and his call is completed thereby.

When the attendant responds to the buzzer 40 229 he is able to find the trouble very quickly owing to the fact that the various switches of the director are retained in their operated positions. When the attendant discovers and remedies the trouble, he operates the 45 push button P momentarily, thereby opening the circuit of relay 205 and relay 227. Relay 227 deenergizes and opens the circuit of the buzzer, and relay 205 deenergizes and removes ground from release trunk conductor 50 70, thereby rendering the director accessible again and at the same time opening the circuit of release relay 201, whereupon the various switches of the director are restored to their normal positions in the hereinbefore 55 described manner.

What is claimed is:

1. In a telephone system in which the telephone numbers are assigned according to a twenty character system of notation, automatic switches operated according to the decimal system of notation, and mechanism for translating from one system of notation to the other to enable the subscribers to operate said switches.

65 2. In a telephone system in which the tele-

phone numbers are assigned according to a twenty character system of notation, automatic switches operated according to the decimal system of notation, a register sender for receiving a called telephone number, and 70 means in said sender for translating the number received and transmitting it to said switches.

3. In a telephone system in which the telephone numbers are assigned according to a 75 twenty character system of notation, automatic switches operated according to the decimal system of notation, and a director for controlling said switches to establish connections corresponding to called telephone 80 numbers, said director comprising registers for receiving the numbers, a sender for controlling the switches, and translating means for changing from one system of notation to the other.

4. In a telephone system in which the telephone numbers are assigned according to a 85 twenty character system of notation, calling devices at the subscribers' stations adapted to send variable series of impulses from one to twenty, automatic switches responsive to a maximum of ten impulses, and a director for receiving the series of impulses corresponding to a called number and translating 90 said series into other series of impulses suitable for operating said switches.

5. In a telephone system, a plurality of offices to each of which is assigned a complete block of telephone numbers, there being another block of numbers divided equally between said offices, a director in one office for receiving calls, means in said director responsive to the calling of any block designation except the last for trunking the call to the corresponding office, and additional 105 means in said director responsive in case the designation of said last mentioned block is called for trunking the call to any one of said offices depending on another part of the telephone number.

6. In a director, a plurality of registers, means for setting said registers in accordance with the digits in a called number, a sender for transmitting a plurality of series of impulses to control the establishment of 110 a complete connection, and translating means intervening between the registers and sender so arranged that each series of impulses except the last is determined by the setting of at least two of said registers, the 115 last of the series of impulses being controlled by the setting of one only of said registers.

7. In a director, a plurality of registers, means for setting said registers in accordance 120 with the digits in a called number, a sender for transmitting a plurality of series of impulses to control the establishment of the connection, said plurality of series of impulses comprising an office code and a 130

plurality of digit series, and translating means intervening between said registers and sender so arranged that a certain one of said registers helps determine the value 5 of the office code and the value of at least one of the series of digit impulses.

8. In a telephone system, a plurality of automatic exchanges, a director in the first exchange including a plurality of registers, 10 switching mechanism in the first exchange controlled in accordance with the setting of a first one of said registers alone for trunking a call to a second exchange, and a group selector in the second exchange controlled 15 in accordance with the setting of three of said registers.

9. In a telephone system, a plurality of automatic exchanges, a director in the first exchange including a plurality of registers, 20 switching mechanism in the first exchange controlled in accordance with the setting of a first one of said registers alone for trunking a call to a second exchange, and a group selector in the second exchange controlled 25 in accordance with the setting of said first register and two other of said registers.

10. In a telephone system, a plurality of automatic exchanges, a director in the first exchange including a plurality of registers, 30 switching mechanism operated under the joint control of only two of said registers for trunking a call to a second exchange, and an office selector in the second exchange operated under the joint control of said two 35 registers and one other register.

11. In a telephone system, a plurality of automatic exchanges, a director in the first exchange including a plurality of digit registers, switching mechanism controlled by 40 less than three registers in the director for trunking a call to a second exchange, and a group selector in the second exchange controlled in accordance with the setting of three of said registers.

45 12. In a telephone system, a plurality of automatic exchanges, a director in the first exchange including a plurality of digit registers, switching mechanism controlled by the director for trunking a call to a second exchange, a group selector in the second exchange operated under the joint control of the first, second, and third registers, and a second group selector in the second exchange operated under the joint control of the second and third registers and independent of the setting of the first register.

55 13. In a telephone system, a plurality of automatic exchanges, a director in the first exchange including a plurality of digit registers, switching mechanism controlled by the director for trunking a call to a second exchange, a group selector in the second exchange operated under the joint control of the first and second registers, and a second group selector in the second exchange op-

erated under the joint control of the second and third registers and independent of the setting of the first register.

14. In a telephone system, a plurality of automatic exchanges, a director in the first 70 exchange including a plurality of digit registers, switching mechanism controlled by the director for trunking a call to a second exchange, a group selector in the second exchange operated under the joint control of the first and second registers, a second group selector in the second exchange operated under the joint control of the second and third registers, and a final connector in the second exchange operated under the joint control of the third and fourth registers. 75

15. In a telephone system, a plurality of automatic exchanges, a director in the first exchange including an office register and a plurality of digit registers, trunk lines extending to a second exchange selectable solely in accordance with the setting of said office register, trunk lines extending to a third exchange selectable in accordance with the setting of said office register and the first digit register, and director controlled switching mechanism in the first exchange for selecting said trunk lines as set forth. 80

16. In a telephone system, a plurality of automatic exchanges, a director in the first exchange including a plurality of registers, and switching mechanism in the first exchange operated under control of a single one of said registers and independent of the particular setting of any of the other registers for trunking a call to a second exchange and operated under control of a plurality of said registers for trunking a call to a third exchange. 85

17. In a telephone system, a plurality of automatic exchanges, a director in the first exchange including a plurality of registers, a final connector in a second exchange, office selectors in the first exchange and group selectors in the second exchange controlled by the director for trunking a call to said connector, and means for operating said connector to accomplish final group selection under control of two of said registers and to accomplish line selection under control of only one of said registers. 90

18. In a director, a plurality of registers for registering a called number, means for transmitting trains of impulses, a device for counting the impulses in each train, and a stop conductor controlling said device and extending serially through the wipers of two of said registers. 105

19. In a director, a plurality of registers, means for transmitting trains of impulses, a device for counting the impulses in each train, and a stop conductor controlling said device and extending serially through the wipers of three of said registers. 110

20. In a director, a plurality of registers, means for transmitting trains of impulses, a device for counting the impulses in each train, a stop conductor controlling said device and extending through a wiper of only one of said registers, and a second stop conductor also controlling said device and extending serially through the wipers of two of said registers. 5
21. In a director, a plurality of registers, means for transmitting trains of impulses, a device for counting the impulses in each train, a stop conductor controlling said device and extending through a wiper of only one of said registers, and a second stop conductor also controlling said device and extending serially through the wipers of three of said registers. 10
22. In a director, a plurality of registers, means for transmitting trains of impulses, a device for counting the impulses in each train, a plurality of stop conductors controlling said device, and wipers in a plurality of said registers included in each of said conductors. 20
23. In a director, a plurality of registers, means for transmitting trains of impulses, a device for counting the impulses in each train, a relay controlled by a wiper of one of said registers, and a stop conductor including contacts of said relay and the wiper of another of said registers. 30
24. In a director, a plurality of registers, means for transmitting trains of impulses, a device for counting the impulses in each train, a group of relays selectable by a wiper of one of said registers, and stop conductors controlling said device and selectable under the joint control of said relays and a wiper of another of said registers. 40
25. In a director, a plurality of single motion registers, each having a bank of only twenty contacts, means for transmitting trains of impulses, a device for counting the impulses in each train, ten stop conductors controlling said device connected, respectively, to the first ten contacts in the bank of one of said registers, and multiple connections from said conductors to the last ten contacts in the bank of the same register. 45
26. In a director, a plurality of single motion registers, each having a bank of only twenty contacts, means for transmitting trains of impulses, a device for counting the impulses in each train, a stop conductor controlling said device and connected in multiple to the first ten contacts in the bank of one of said registers, and a second stop conductor connected in multiple to the last ten contacts in the bank of the same register. 50
27. In a director, a plurality of registers, means for transmitting trains of impulses, a device for counting the impulses in each train, stop conductors selectable by said registers for controlling said device, a relay 60
- having a winding connected to the last one of said stop conductors, and contacts on said relay for rendering said transmitting means inoperative. 70
28. In a director, a plurality of registers, means for transmitting trains of impulses, a device for counting the impulses in each train, stop conductors selectable by said registers for controlling said device, a relay connected to the last one of said stop conductors, contacts on said relay for rendering said transmitting means inoperative, a locking circuit for said relay, and an alarm relay included in said locking circuit. 75
29. In a director, a plurality of registers, means for transmitting trains of impulses, a device for counting the impulses in each train, stop conductors selectable by said registers for controlling said device, and an alarm relay connected to one of the stop conductors and operated in case any selected one of said conductors becomes defective. 80
30. In a director, a plurality of registers, means for transmitting trains of impulses, a device for counting the impulses in each train, stop conductors controlling said device, said device having a wiper which connects with said stop conductors, wipers on said registers for selecting certain conductors, and an alarm relay operated over a circuit extending through said first mentioned wiper in case an operated register wiper is out of adjustment and fails to connect with a stop conductor. 90
31. In a telephone system, a subscriber's line, a calling device at the station on said line adapted to send variable series of impulses from one to twenty, automatic switches responsive to a maximum of ten impulses, means for extending said line when calling to one of said switches, a director, means responsive to the call for extending a branch connection to said director, means in said director for registering the series of impulses sent out by said calling device, and means in said director controlled by said registering means for transmitting translated series of impulses to operate said switches. 100
32. In an automatic telephone system wherein there is provided a line, a plurality of selectors, a plurality of directors, and means responsive to the initiation of a call over the line for seizing an idle selector and an idle director, and for connecting the calling line to the receiving end of the director, and the selector to the transmitting end of the director, the combination with the director of means for transmitting an alternating current to the calling line over one of the conductors connecting the director with the selector. 110
33. In an automatic telephone system wherein there is provided a line, a plurality of selectors, a plurality of directors, and means responsive to the initiation of a call 120

- over the line for seizing an idle selector and an idle director, and for connecting the calling line to the receiving end of the director, and the selector to the transmitting end of the director, the combination with the director of means for transmitting an alternating current to the calling line over one of the conductors connecting the director with the selector, and means in the director effective upon the occurrence of a defective condition in the transmitting apparatus of the director for rendering said last named means effective.
34. In an automatic telephone system wherein there is provided a line, a plurality of selectors, a plurality of directors, and means responsive to the initiation of a call over the line for seizing an idle selector and an idle director and for connecting the calling line to the receiving end of the director, and the selector to the transmitting end of the director, the combination with the director of means for transmitting an alternating current to the calling line over one of the conductors connecting the director with the selector, and means controlled by said last named means for preventing the transmission of digit impulses from the director to the selector.
35. In a director controlled from a calling line, a plurality of registers, means for transmitting trains of impulses, a device for counting the impulses in each train, stop conductors selectable by said registers for controlling said device, means effective in case a suitable stop conductor is not encountered after a given number of impulses in a train have been transmitted for stopping the additional transmission of impulses, and means controlled by said last named means for transmitting a characteristic signal to the calling line in lieu of the additional trains of impulses.
36. In a telephone system, a director, a line, a selector, means for establishing a connection from the line to the receiving end of the director and for establishing a connection from the selector to the transmitting end of the director, means for transmitting digit impulses from the director over the last named connection, and means for transmitting current over the line to indicate that impulses are being transmitted.
37. In a telephone system, a line, a selector, a director having a receiving circuit for receiving impulses and a transmitting circuit for transmitting impulses, means for establishing a connection from the line to the receiving circuit and from the transmitting circuit to the selector, and means establishing a connection between the transmitting circuit and the line for indicating that transmission is taking place.

38. In a telephone system, a director having an office registering portion and a station registering portion, means for setting said portions to desired positions, certain of the positions on the office registering portion representing each a certain office and another position representing a group of offices, and means depending upon the position of the station registering portion in the event the director has been set to the last named position for determining the desired office of the group.

39. In a telephone system, a director, means for transmitting a plurality of groups of office designating and station designating digit impulses to the director, means for selecting a single office or a group of offices depending upon the value of the office designating digit impulses, and means effective if a group of offices have been selected and depending upon the value of a station designating group of digit impulses for selecting a desired office of the group.

40. In a telephone system, a director, registers in said director set in accordance with a desired telephone number, said telephone number having an office designating portion and a station designating portion, means for selecting a single office or a group of offices depending upon the value of the office designating portion of the number, and means effective if a group of offices have been selected and depending upon the value of the station designating portion for selecting a desired office of the group.

41. In a telephone system a director including a plurality of registers for receiving groups of digit impulses, a sequence switch for distributing the incoming groups of impulses to the registers, means in the director for transmitting groups of digit impulses, said sequence switch having a plurality of wipers, each for controlling the initiation of the transmission of one of the groups of impulses.

42. In a telephone system, a director, means for transmitting office designating and station designating groups of impulses to the director, a switch having as many wipers as there are groups of station designating impulses, all of the wipers being operated with each group of station designating impulses transmitted to the director, means for transmitting office designating and station designating groups of impulses from the direction, each of the wipers controlling the initiation of the transmission of one of the last mentioned groups of station designating impulses.

In witness whereof, I hereunto subscribe my name this 22d day of June, A. D., 1923.

RODNEY G. RICHARDSON.
